CASEMENT WINDOW OPERATING MEANS

Henry Bianco, Baltimore, Md., assignor to Campbell Metal Window Corporation, New York, N. Y., a corporation of Maryland

Application April 30, 1936, Serial No. 77,075

4 Claims. (Cl. 268—117)

The general object of the present invention is to provide improved means for adjusting a casement window into, and maintaining it in different positions.

5 A more specific object of the present invention is to provide improvements in a casement window arrangement of the kind in which the window sash is biased for movement from its fully closed position into its wide open position, and may 10 be adjusted into, and held in, different open positions, and may be locked in its closed position by manual adjustments given the inner end portion of a flexible operating element connected at one end to the sash and extending from the 15 latter to the inner side of the casing, and cooperating with means carried by the casing, and including parts through which the said adjustments of said element lock the sash to, or unlock it from the casing, when the sash is in its 20 closed position, and, when the sash is in an open position, cause said element to be either gripped at one or another point along its length, or released, and thereby hold the sash in one or another open position, or permit opening and 25 closing movements of the sash.

In a preferred form of the improved arrangement, the sash is given its bias or opening movement by spring hinge connections between the sash and the window casing, and the flexible operating connection through the window sash is 30 preferably a light pull chain, and the cooperating means carried by the casing includes a member which is pivoted to the casing and formed with a guide passage for the flexible element, and 35 is adapted to be given pivotal movements by lateral adjustments of the portion of the element at the inner end of said guide passage, and is provided with a locking hook, moved by the pivotal movements of said member into and out of locking engagement with the sash when the latter is in its closed position.

In the preferred embodiment of the invention illustrated and described in detail herein, the parts by which, as a result of lateral movements 45 of the inner end portion of the flexible or pull chain element the latter is gripped at one or more points along its length, and thereby held against longitudinal movement, or is released to permit such longitudinal movements, comprise 50 a keyhole opening formed in the portion of the pivoted member at the end thereof remote from its pivot, and resilient means mounted on the member and tending to hold an adjacent link of the pull chain in a portion of the keyhole opening, which is too narrow to permit longitudinal 55

movement of the pull chain therethrough. Lateral movement of the inner end portion of the pull chain in the direction required to turn the pivoted member out of its sash locking position, if carried far enough, displaces the said resilient 5 means to permit movement of the pull chain out of the narrow portion of the keyhole opening, into a larger portion of said opening through which the pull chain is longitudinally movable. With the described construction, with the pivoted 10 member in the position into which it is turned in unlocking the sash, the sash may be secured in any position intermediate its fully closed and wide open position, by entering a corresponding link of the pull chain in the narrow portion of 15 the keyhole opening.

The various features of novelty which characterize my invention are pointed out with particularity in the claims annexed to and forming a part of this specification. For a better understanding of the invention, however, its advantages, and specific objects attained with its use, reference should be had to the accompanying drawing and descriptive matter in which I have illustrated and described a preferred embodiment of the invention. 20 25

Of the drawing:

Fig. 1 is an elevation of a casement window construction as seen from its inner side;

Fig. 2 is a horizontal section on the broken line 30 2—2 of Fig. 1;

Fig. 3 is a partial section on the line 3—3 of Fig. 1;

Fig. 4 is a section on the line 4—4 of Fig. 3;

Fig. 5 is a fragmentary elevation of a portion 35 of the window casing and sash construction shown in Fig. 1, and taken at right angles to that figure; and

Fig. 6 is a perspective view of a chain guiding and holding and window locking element of 40 the construction shown in Figs. 1—4.

The window construction shown in the drawing comprises a metallic window casing element 1 adapted for inclusion in a building wall, and in the form of a rectangular frame surrounding a 45 rectangular window opening adapted to be enclosed by a metallic window sash member 2, which is hinge connected to the casing frame 1 at one side of the latter. As shown in Fig. 2, the casing frame is of Z bar cross section comprising inner 50 and outer parallel flange or rib portions 3 and 4 connected by a transverse web portion 5. The sash 2 comprises a marginal frame portion of similar cross section, and in the closed position of the sash, its inner and outer frame flanges 55

6 and 7 abut against the casing flanges 3 and 4 respectively, with the transverse sash web 8 alongside and spaced some distance away from the casing web portion 4. As shown, the sash comprises central vertical and horizontal bar portions 9 and 10 respectively, which in conjunction with the sash frame, provides seats for four glass panes 11. The latter may be anchored against their seats in any usual or suitable manner which need not be illustrated or described herein, as the invention is not concerned with the mounting of the window panes, or with the shape or number of the latter.

The window sash 2 is hinged at one side to the corresponding side of the window casing by upper and lower hinge connections, each shown as comprising a bracket 12 welded or otherwise attached to, and projecting outwardly from, the outer flange 4 of the casing, a generally similar bracket part 13 welded or otherwise attached to the outer flange 7 of the window casing, and a bolt or analogous connection 14 between the two brackets and serving as the hinge pintle. Each hinge connection includes a spring 15 shown as comprising a body portion of spring wire coiled about a hinge pintle, and tangential end extensions 16 and 17. The extension 16 passes through an opening formed for the purpose in a lug or projection 18 from the adjacent side of the corresponding bracket 12. The other spring end extension 17 lies in the corner space at the adjacent side of the bracket 13 and in front of a vertically extending flange portion 19 of the bracket part 13. The spring 15 is under tension tending to spread its end portions 16 and 17 apart and thereby subjects the sash to a constantly acting spring opening force.

In its preferred form, the flexible window operating element 20 is a chain, comprising links each of which can be separately moved laterally into a portion of the hereinafter described keyhole opening which is too narrow to permit longitudinal movement of the chain therethrough, but when laterally displaced in a larger portion of the keyhole opening, is longitudinally movable through said opening. Ordinarily, and as shown, the element 20 is a chain formed with sheet metal links. As shown, the chain is connected to the sash at the free edge of the latter and about midway between the top and bottom of the sash by means of a hook or eye part 21, having a threaded stem passing through the sash flange 6, and held in place by a nut 21' bearing against the outer side of the flange.

As shown, the chain 20 extends through and is freely movable in the upper portion of a vertically elongated opening 22, formed in the casing flange 3. The chain 20 also extends through the upper one of openings 23 and 24 formed in a metallic part 25, secured to the window casing flange 3 at the front or room side of the latter. When the sash is in its closed position, the attachment part 21 is in register with the upper portion of the sash opening 22 and with the opening 23 in the part 25. The last mentioned opening is large enough to permit free longitudinal movement of the chain therethrough.

The part 25 as shown, comprises a bar like body portion formed adjacent its ends with holes 26 for securing bolts passing through those holes and threaded into the casing flange 3. At its front side, the member 25 is formed with lugs or ears 27 serving as hinge brackets or ears apertured to receive the ends of a pivot pin 28, on which a lever member 29 is journaled.

The lever 29 comprises a flat hook portion or

locking part 30 through which the pivot pin 28 extends and which is received between the ears 27 and extends through the opening 24 in part 25 and through the lower portion of the opening 22 in the casing flange 3 into the space alongside the casing web 5, and between it and the sash web 8, when the sash is in its closed position. As shown, a portion of the member 29 in front of the part 25 is thicker than the hook portion 30 and comprises shoulders 31 in abutting relation with the front or free edges of the hinge ears 27. The thickened portion of the lever part 29 is also formed with an elongated guide way or passage 33 for the chain 20. The passage 33 extends transversely to, and is laterally displaced from the pivot pin 28. As shown, the passage 33 comprises a cylindrical portion at its end adjacent the sash, an intermediate portion open at one side, and a keyhole shaped portion which is formed in a transverse portion 34 of the lever 29 at its end 20 remote from the sash, and comprises a rounded portion 35 and a narrower portion 36. The chain 20 is freely movable in the large diameter part 35 of the keyhole opening and in the portion of the passage 33 between said opening and the sash 25 end of the passage.

The keyhole opening portion 36 is wide enough to receive the shank or body portions of the links of the chain 20, but when the shank or body portion of a link of the chain 20 is received in said portion 36, longitudinal movement of the chain is prevented, since the portion 36 is not wide enough for the passage of the linked portions of each end to end pair of chain links. Normally, the shank portion of one or another of the links of the chain 20 is held in the narrower keyhole opening portion 36 by the chain engaging part 37 of a member 38. The latter is shown as a lever received in an elongated recess 41 formed in a portion of member 29 alongside the passage 33, and journaled on a pivot pin 39 having its ends mounted in the side walls of the recess 41, a spring 40 normally maintains the lever 38 held in the position in which its end portion 37 holds a link of the chain in the keyhole opening portion 36. The spring 40, as shown, is a piece of spring wire of hairpin shape, looped about the pivot pin 39 and having its legs received in the portion of the recess at the opposite side of pin 39 from the chain engaging part 37, one leg of the spring bearing 50 against the wall of the recess 41 between the latter and the passage 33, and the other spring leg bears against the adjacent side of the lever 38.

In the full line position of the parts shown in Fig. 3, the sash is positively locked in its closed position by engagement of the hook portion 30 of the lever 29 with the sash carried locking part 42. The latter is shown as a projection from a bar-like member 43 screw connected to the sash web 8. The engaging surfaces of the hook 30 and the locking part 42 are preferably rounded and shaped as shown in Fig. 3, to engage with a camming or wedging action and thereby hold the sash flanges 6 and 7 in snug engagement with the casing flanges 3 and 4, respectively, when the sash is in its locked position. As shown in full lines in Fig. 3, a link of the chain 20 is received in the narrow slot portion 36 of the keyhole opening formed by the portions 35 and 36, and the chain engaging part 37 is in position to prevent movement of said link out of the slot 36, but with the hook 30 in engagement with the part 42, as shown in Fig. 3, it is not directly important whether the chain is received in the narrow slot

portion 36, or in the rounded portion 35 of the keyhole opening.

Movement of the lever 29 from the full line position shown in Fig. 3 into the dotted line position shown in that figure, turns the hook 30 out of engagement with the sash carried locking part 42, and makes the position of the sash dependent on the longitudinal adjustment of the pull chain 20. When the portion of the latter at the inner 10 side of the window casing is deflected counter-clockwise, as shown in dotted lines in Fig. 3, out of alignment with the passage 33 in the member 29, the member 38 is moved against the action of its bias spring 40 as required for the movement 15 of the chain out of the narrow portion 36, and into the rounded portion 35 of the keyhole opening at the end of the passage 33. In that condition of the apparatus, the sash will turn in the opening or closing direction, accordingly, as the 20 longitudinal tension of the portion of the chain between the sash and the hand of the operator holding an inner end portion of the chain, is less than, or greater than, the sash opening bias force of the spring hinge connections between the 25 sash and the casing. With the lever 29 in the dotted line position shown in Fig. 3, a clockwise adjustment of the inner end portion of the chain away from the position of said portion shown in dotted lines in Fig. 3, will permit the part 37 30 of the member 38 to carry a link of the chain into the narrow portion 36 of the keyhole opening, and thereby lock the chain against longitudinal movement in the passage 33 of the lever 29. If the inner end of the chain is then released, the 35 sash will be held in whatever open position it may then be in, as a result of the engagement of a chain link with the walls of the narrow slot portion 36, and the engagement of the upper ends of the shoulder portions 31 of the lever 29 with the shoulder portions 25' of the hinge ears 27 of the 40 part 25.

As will be apparent, all of the operative adjustments of the chain 20 and lever 29 and member 38 just mentioned, may be effected by movements given to or permitted the inner end portion 45 of the chain by the hand of the operator, and by such movements the parts may be returned to their positions shown in full lines in Fig. 3. As will be apparent, the engagement of the member 29, when in its dotted line position with the shoulders 25' of the part 25, prevents further counter-clockwise adjustment of the lever 29, either under the pull of the chain when the window is secured in a partly open position, or as a result of the counter-clockwise adjustment 50 of the inner end portion of the chain required to move the member 38 against the action of its bias spring 40.

The window operating mechanism illustrated and described, is simple, compact and relatively inexpensive to manufacture, and its operation is simple and easily effected. The member 25 may well be provided, as shown, with a hook 44, which may be used in locking a window screen in place, and it is one of the advantages of the present invention that the window opening screen may be mounted in the casing so that it does not need to be adjusted in the normal adjustment of the window between its closed and locked position and any of its open positions.

While in accordance with the provisions of the statutes, I have illustrated and described a provided embodiment of the present invention, those skilled in the art will realize that changes in the 75 form of the apparatus disclosed may be made

without departing from the spirit of my invention as set forth in the appended claims and that in some cases certain features of my invention may be used to advantage without a corresponding use of other features.

Having now described my invention, what I claim as new and desire to secure by Letters Patent, is:

1. In a casement window, a window casing, a sash hinged to said casing to turn between open and closed position, means tending to turn said sash away from and opposing its return to its closed position, a flexible window operating element connected at one end to said sash and having its other end at the inner side of the window, 10 a sash locking lever pivotally mounted on said casing to turn into and out of locking engagement with said sash and formed with a guide passage receiving an intermediate portion of said element and adapted to be turned into and out of locking engagement with said sash by lateral movements of the portion of the element extending away from said passage at the inner side of the window, and means mounted on said lever and rendered operative and inoperative to hold 15 said element against longitudinal movement in said passage by the said lateral movements.

2. In a casement window, a window casing, a sash hinged to said casing to turn between open and closed position, means tending to turn said sash away from and opposing its return to its closed position, a flexible window operating element connected at one end to said sash and having its other end at the inner side of the window, 20 a sash locking lever pivotally mounted on said casing to turn into and out of locking engagement with said sash and formed with a guide passage receiving an intermediate portion of said element and adapted to be turned into and out of locking engagement with said sash by lateral movements of the portion of the element extending away from said passage at the inner side of the window, and a movable part mounted on 25 said lever and biased for movement into a position in which it projects across said passage and holds said element against longitudinal movement in said passageway and adapted to be moved out of said passage to permit said longitudinal movement of said element by the said lateral movements of said element.

3. In a casement window, a window casing, a sash hinged to said casing to turn between open and closed position, means tending to turn said sash away from and opposing its return to its closed position, a window operating chain connected at one end to said sash and having its other end at the inner side of the window, a sash locking lever pivotally mounted on said casing to turn into and out of locking engagement with said sash and formed with a guide passage receiving an intermediate portion of said element and adapted to be turned into and out of locking engagement with said sash by lateral movements of the portion of the element extending away from said passage at the inner side of the window, said passage including a narrow portion alongside of a wider portion, and adapted to receive a chain link and to prevent movement thereof in the direction of the length of the chain, and means mounted on said lever and tending to hold a link 30 of said chain in said narrow portion and adapted to be rendered inoperative by said lateral movements of said element portion.

4. In a casement window, a window casing, a sash hinged to said casing to turn between open 35

- and closed position, means tending to turn said sash away from and opposing its return to its closed position, a flexible window operating element connected at one end to said sash and having its other end at the inner side of the window, a sash locking lever pivotally mounted on said casing to turn into and out of locking engagement with said sash and formed with a guide passage receiving an intermediate portion of said element and adapted to be turned into and out of locking engagement with said sash by lateral movements of the portion of the element extending

away from said passage at the inner side of the window, means mounted on said lever and rendered operative and inoperative to hold said element against longitudinal movement in said passage by the said lateral movements, and stationary means supported by said casing and adapted for engagement by said lever to hold the latter against turning movement due to the tension of said element when the latter is held against longitudinal movement in said passage. 5 10

HENRY BIANCO.
